(57) **CLAIM**

The ornamental design for a pizza hood, as shown and described.

DESCRIPTION

FIG. 1 is a perspective view of a pizza hood showing my new design;

FIG. 2 is a front elevation view thereof;

FIG. 3 is a rear elevation view thereof;

FIG. 4 is a left-side elevation view thereof;

FIG. 5 is a right-side elevation view thereof;

FIG. 6 is a top plan view thereof;

FIG. 7 is a bottom plan view thereof;

FIG. 8 is another perspective view thereof shown in a configuration of use with an environment grill;

FIG. 9 is an enlarged view of the encircled area 9 of FIG. 3; and,

FIG. 10 is an enlarged view of the encircled area 10 of FIG. 7.

The broken line showing of a grill in FIG. 8 depicts environment and forms no part of the claimed design. The broken lines shown in FIGS. 9 and 10 depict portions of the pizza hood that form no part of the claimed design. The dot-dash-dot broken lines depict the enlarged view boundaries that form no part of the claimed design.
